Primary Examiner — Keith J Wilson(74) *Attorney, Agent, or Firm* — Shumaker, Loop & Kendrick, LLP; James D. Miller(57) **CLAIM**

The ornamental design for a grass hole system, as shown and described.

DESCRIPTION

FIG. 1 is a bottom perspective view of an embodiment of a grass hole system showing my new design.

FIG. 2 is a top perspective view thereof;

FIG. 3 is a bottom plan view thereof;

FIG. 4 is a top plan view thereof;

FIG. 5 is a front elevational view thereof;

FIG. 6 is a cross-sectional elevational view thereof taken along line 6-6 in FIG. 4; and,

FIG. 7 is a fragmentary elevational view thereof taken within highlighted circle 7 of FIG. 5.

The ornamental design which is claimed is shown in solid lines in the drawings.

1 Claim, 6 Drawing Sheets(56)
